UNITED STATES PATENT OFFICE

HANS SENGBUSCH, OF VILLA PARK, ILLINOIS, ASSIGNOR TO RESERVE HOLDING COMPANY, OF CHICAGO, ILLINOIS, A CORPORATION OF DELAWARE

DESIGN FOR A CASING FOR AN IMPULSE-SENDING MACHINE

Application filed April 19, 1930. Serial No. 35,314. Term of patent 14 years.

To all whom it may concern:

Be it known that I, HANS SENGBUSCH, a citizen of the United States of America, residing at Villa Park, DuPage County, Illinois, have invented a new, original, and ornamental Design for a Casing for an Impulse-Sending Machine, of which the following is a specification, reference being had to the accompanying drawing, forming a part thereof.

The figure is a perspective view of a casing

for an impulse sending machine, showing my new design. The opposite side of the casing is like the side which is shown, while the back is substantially plain.

I claim:

The ornamental design for a casing for an impulse sending machine, as shown and described.

In testimony whereof, I have hereunto set my hand this 17th day of April, 1930.

HANS SENGBUSCH.
